UNITED STATES PATENT OFFICE.

AMAND DELILLE DAIGRE, OF LEVALLOIS-PERRET, FRANCE.

PROTECTIVE ARMORING.

1,324,234.

Specification of Letters Patent.

Patented Dec. 9, 1919.

Application filed April 11, 1917. Serial No. 161,353.

To all whom it may concern:

Be it known that I, AMAND DELILLE DAIGRE, a citizen of the French Republic, and residing at 39 Route de la Révolte, Levallois-Perret, Seine, France, have invented 5 certain new and useful Protective Armoring, of which the following is a specification.

This invention relates to protective armoring either in the form of separate shields 10 to be worn by the combatants or in the form of plating for constructing shelters, protecting screens, cupolas, gun and rifle shields, or armor plating for protecting the important parts of aeroplanes, dirigible balloons 15 and so forth. It is the object of the invention to provide a light form of armoring suitable for the above purposes, and wherein in a metal plate is coated and cushioned by 20 a layer of a softer material.

According to this invention armoring is composed by grouping together metal plates and sheets of an elastic or plastic material; these plates and sheets are variable in number 25 according to the purpose in view and are superposed and arranged alternately.

The assemblage of one or a plurality of metal plates and one or a plurality of sheets of plastic material forms armoring which 30 for a given surface furnishes a resistance to penetration of projectiles considerably superior to that obtained with a single plate of the same metal, size and weight.

The metal plate may be of any suitable 35 metal such as steel, aluminium and so forth, according to the degree of resistance and lightness which it is desired to obtain and according to the conditions of fighting to which the combatant or object protected are 40 to be exposed. The armor may be either in the form of a single piece or of a plurality of pieces, which may be in the form of laminae, scales and so forth, hooked or otherwise connected one to another so as to form a 45 solid, flexible and pliant entirety as may be required.

The armor plating or shield may be made in a number of different ways.

For example a shield may be formed of 50 two metal plates between which is interposed the sheet of resilient material; in this case the projectile will first strike a metal plate. It is also possible to place alternately 55 a number of metal plates and sheets of resilient material in order to form highly resistant shields. The arrangement of the

plates and sheets may be such that the projectile will first strike either a metal plate or a sheet of resilient material. A shield may also be formed from a single metal 60 sheet and a sheet of resilient material.

In general, it appears to be advantageous for the projectile to be allowed to strike the resilient material first.

A form of construction which is particularly good is that which consists of a sheet of steel placed between two sheets of resilient material. This form of construction which will be described later, appears to present the highest resistance for a given 70 size of surface and weight and is particularly adapted for the construction of separate protecting shields for combatants.

In the accompanying drawings, Figures 1, 1^a, 2 and 3 show an example of construction of a shield for personal wear, according to this invention, formed of a plate or plates of steel alternating with sheets of resilient material; Fig. 1 is a section; Fig. 1^a is a modification of the device shown in 80 Fig. 1; Fig. 2 is a front view with portions broken away so as to show the different layers of which the shield is composed; and Fig. 3 is a rear view with the hooks for attachment. Figs. 4, 5 and 6 illustrate the 85 manner in which, for example, such a shield may be carried or worn by a soldier.

The steel plate 1, of any suitable shape is surrounded by a metal frame 2 which may be formed of aluminium of U-section. 90

The steel plate 1 thus surrounded by the aluminium frame 2 is coated on its two sides with sheets 4 of resilient material, and the whole is inclosed in a casing 5 which is generally of fabric though it may be formed 95 for example of thin metal which is only adapted to protect the resilient material during use against wear and tear.

Such substances as the following may be used as the resilient material, that is to say, 100 gums, india-rubber, artificial rubber and rubber substitutes, or other suitable substance with the addition of a suitable precipitant or coagulant.

The resilient material may be combined 105 with a vegetable or mineral body, animal or vegetable textures or fibers, asbestos and so forth.

In order to apply this resilient material, when mixtures of glues or gelatins and glycerin are to be used, it may for example be 110 cast in a water bath, and then filled in un-

der pressure, or even simply by running it into a mold into which has just been placed the metal plate which is to be coated with this material or which is to be covered completely thereby.

The grooves formed between the edges of the metal frame 2 and the steel plate 1 are filled with a resilient material 3 which is denser than that forming the sheets 4; this packing 3 is adapted to stop any splinters from the projectile which after the shock are driven parallel to the plate and still possess a considerable kinetic energy.

The material 3 may be of the same composition as the resilient material 4, but in this case the material is subjected to a greater pressure so as to secure the desired greater density.

Referring now to Figs. 4 to 6, it will be seen that a single long band, strap or belt 6 is placed on the wearer, its ends 6' being passed around the waist portion of the strap and doubled back and fastened at any desired point, according to the size of the wearer, by means of buttons 8 which engage in the holes 7 permitting of adjustment; these buttons at the same time form hooks.

On the part of the strap forming the front portion of the belt is arranged a plate 9 provided with a hook 8 and suitable openings through which the belt is passed.

On the back of the shield are secured three

rings 10 (Fig. 3) adapted for engagement with the three hooks 8 (Fig. 4) so that the shield may be worn as shown in Fig. 5.

It will be understood that the shape of the shield and its accessory members may be varied according to the use and method of attachment and securing the same, without departing from the spirit of the invention.

Having thus described my invention what I claim as new and desire to secure by Letters Patent is:—

1. Protective armoring adapted to resist bullets and shell splinters, and comprising a metal plate, a frame around said plate, a resilient material between the frame and the plate, a layer of resilient material on both sides of the plate and a casing around the frame and resilient material.

2. Protective armoring adapted to resist bullets and shell splinters, and comprising a metal plate, a frame around said plate, a dense resilient material between the frame and the plate, a layer of resilient material on both sides of the plate, and a casing around the frame and resilient material.

3. A body shield comprising a metal plate, a frame around said plate, a dense resilient material between the frame and the plate, a layer of resilient material on both sides of the plate, an inclosing casing, rings on the shield, and a strap having hooks for engaging with the rings.

AMAND DELILLE DAIGRE.
